PLAYGROUND APPARATUS

James F. Patterson, San Jose, Calif.

Application February 24, 1930. Serial No. 430,869

7 Claims. (Cl. 272—60)

It is one object of the invention to provide a structure of the character indicated that will not only enable children to climb readily thereover and therethrough whereby to satisfy their natural inclination to climb, but that will also enable them to compete with each other in travelling over parallel courses on annular paths spaced a distance from the ground.

It is also an object of the invention to provide a structure of the character indicated that offers equal facilities for a variety of exercises for children of varying ages and sizes.

In the drawing:

Figure 1 is a plan view of one-half of a structure embodying my invention.

Figure 2 is an elevation of the structure part broken away.

Figure 3 is a perspective illustration of a portion of the structure to show the relative positions of the radial bars.

Figure 4 is a plan view of one-half of another embodiment of the invention.

Figure 5 is a vertical transverse section through one-half of the structure indicated in Figure 4.

In effecting my invention I provide a central vertically positioned support 1 seated in a concrete base 2. At 3 are shown a plurality of equally spaced vertical supports arranged in a circle about support 1 and in concentric relation thereto, each of these supports being set in a concrete base 4. Secured to these supports 3 in any suitable manner as by bolts 5 are vertically spaced annular tie and supporting members 5a 30 6, 7 and 8, each member lying in a horizontal plane and completely encircling the supports 3 as shown.

At 9 are shown a plurality of radial members, in the present case eight in number, inserted between the central support 1 and the supporting members 3 which are likewise eight in number. The radial members 9 are, in the present case, spaced about eighteen inches from the tie 5a and lie in a common horizontal plane, each radial member being secured to the central post 1 by means of the collar 10 and any suitable fastening means as 11, and to the member 6 at its outer end by a bolt as 12. An annular climbing bar 13 is mounted on the radial members 9 in concentric relation to the central post 1 as shown.

The parts 14 to 18, inclusive, are duplicates of the parts 9-13 and are similarly arranged in a horizontal plane spaced some two feet above them, but the radial members 14 are offset relative to the corresponding parts 9 below, and be-

ing, in effect, two horizontally disposed wheels with their spokes out of alignment.

At 19, 20, 21, 22, 23 is a structure similar to 9-13 and 14-18 and spaced, in the present case, about two feet above the parts 14-18 with the 60 radial members 19 offset with relation to members 14 in the same manner and to the same degree that members 14 are offset with relation to member 9.

In viewing the structure from above the radial 65 members 9, 14 and 19 appear equally spaced while the annular bars 13, 18 and 23 are in alignment.

On the topmost climbing bar 23 are mounted vertical supports 24 surmounted by an annular hand bar as 25.

The methods of play permitted by a structure of this type are varied. Children naturally move along curved lines or in circles when at play, and by arranging the uprights 3 in a circle they may follow their natural inclination to run around 75 the structure and climb upon it at any point. When mounted upon bar 8 they may walk around the structure by grasping the upper parts with their hands, or they may climb vertically to bars 9 and 10, or they may climb along bars 9 to the 80 center post 1.

A child on bar 9 may move toward the center of the structure and crawl around in a circle on bar 13, or he may climb angularly and in a circle to bars 14 and 19 and thence to hand bar 25.

In addition to its particular advantages for climbing, this structure provides a maximum of efficiency with a minimum of material and labor costs, and permits the radial members to be used 85 as trapeze bars since no one is directly over another.

In the form of the invention shown in Figures 4 and 5, the single central support 1 is omitted and an annular structure is provided for the support of the inner ends of the radial members 9, 95 14, and 19. This structure comprises vertical supports as 26 and horizontal tie members 27, 28, 29 concentrically arranged relative to the outer structure 3-8 and forming a central well 30. Any desired number of the radial climbing 100 bars may be carried across the well as indicated at 31 and 32.

Additional climbing facilities are provided by this construction since children may climb up and down and around the center of the apparatus as well as its outside, and exceptional opportunity is offered for so arranging the cross bars as 31, 32 whereby they may be freely used 105 as trapeze bars.

Each of these embodiments of the invention 110

permits a child to travel about continuously in a circle without interference, either by reaching from one radial bar to the next or by grasping an upper radial bar and swinging from one lower radial bar to the next one in the same horizontal plane.

It is to be understood, of course, that while I have herein shown and described but one specific embodiment of the invention, changes in form, 10 construction, and method of assembly may be made within the scope of the appended claims.

I claim:

1. A playground apparatus comprising, a central support, a plurality of angularly disposed supports concentrically positioned relative to the central support, vertically spaced members connecting the angularly disposed supports, and radially disposed bars connecting the central support and the annular structure.
- 20 2. A playground apparatus comprising, a central support, an annular structure including spaced vertical supports and vertically spaced horizontally disposed connecting bars concentrically arranged relative to the central support, and vertically spaced horizontally disposed radial bars connecting the central support and the surrounding structure.
- 30 3. A playground apparatus comprising, a central vertical support, an annular structure including spaced vertical supports and vertically spaced horizontally disposed connecting bars concentrically arranged relative to the central support, a plurality of series of vertically spaced horizontally disposed radial bars connecting the central support and the surrounding structure, the radial bars of one series being offset with relation to the radial bars of another series.

4. A playground apparatus comprising, a central vertical support, an annular structure including spaced vertical supports and vertically spaced horizontally disposed connecting bars concentrically arranged relative to the central support, a plurality of series of vertically spaced horizontally disposed radial bars connecting the central support and the surrounding structure, and an annular bar mounted upon each series on radial bars in concentric relation to the central bar and spaced therefrom.

5. A playground apparatus comprising, a central vertical support, a plurality of series of vertically spaced and horizontally disposed radially arranged climbing bars mounted thereon, supporting means for the outer ends of the radial bars, the radial bars of each series being offset with respect to the corresponding bars of adjoining series whereby to provide an annularly diagonal climbing sequence.

6. A playground apparatus comprising, a plurality of series of vertically spaced and horizontally disposed radially arranged climbing bars, the radial bars of each series being offset with respect to the corresponding bars of adjoining series whereby to provide an annularly diagonal climbing sequence, and supporting means for the inner and outer portions of the several series.

7. A playground apparatus comprising, an annular central support forming a well, an annular outer supporting structure, and radially disposed bars disposed in vertically spaced horizontal planes mounted on said supports.

JAMES F. PATTERSON. 110
